TENSIONING DEVICE

Clifford H. Ramsey, Glen Rock, N. J.

Application January 21, 1937, Serial No. 121,717

3 Claims. (Cl. 74—242.11)

This invention relates to so-called "Palmer" machines, to wit, in which an endless quite thick flexible element (known as a blanket) of considerable width and longitudinal extent is made to travel around and with a rotating drum in such manner that a fabric to be treated may be entered between the blanket and drum and, having travelled between them and more or less completely around the drum, issue from between them.

In order to provide for admission of the fabric to and its delivery from between the blanket and drum the blanket is arranged to form what may be termed two loops, one of which embraces the drum directly, except for the intervention of the fabric, and the other of which embraces the first loop, there being guides which maintain bends or bights in the blanket where the two loops merge into each other and other guides for the relatively outer loop. One of the guides is usually shiftable for varying the tension of the blanket according to the requirements of the particular fabric being treated.

Heretofore there has been no means by which it could be determined just what the tension of the blanket was. This was left entirely to the skill of the attendant. Of course this was open to the fault that he might neglect to have the tension precisely sufficient for any particular piece of fabric even if it was within the possibilities of his skill to make it so. But a more serious fault was that he might unwittingly leave the tension excessive with respect to any particular piece of fabric with the result that the blanket would be tensioned to a degree not necessary, and of course the more usual this condition obtains the shorter is the life of the blanket. Sometimes the blanket is, through carelessness or lack of skill, even operated at a tension so high as to reduce the blanket to a no longer serviceable condition.

Since the blankets usually cost an amount running into four figures—sometimes as much as \$1100—the possibilities in respect to deterioration or incapacity of the blanket for continued performance of its proper function will be obvious.

By this invention I provide novel means for varying the tension of the blanket as well as for indicating the degree of such tension.

50 In the drawings,

Fig. 1 is a side elevation of a "Palmer" machine embodying this invention;

Fig. 2 is an enlarged side elevation of a fragment thereof at the left-hand upper corner of 55 Fig. 1;

Fig. 3 is a section on line 3—3, Fig. 2;

Fig. 4 is an elevation of certain parts shown in Fig. 3, viewed from the right, the housing and another part appearing in section; and

Figs. 5 and 6 are, respectively, inside and edge elevations of a certain disk 16.

In the opposite sides 1 (only one being shown) of the frame is journaled the mentioned drum 2. The endless blanket exists, as usual, with a part 3a thereof forming its first-mentioned loop and the remaining part 3b generally forming a loop within which is the first-named loop. Where these loops merge they form bights or bends (at the right) supported by the usual guides 4 and 5, there being a space 6 between such bights by which the fabric may on the one hand enter and on the other depart from between the blanket and drum. At 7 is a smaller drum journaled in the frame and around which the blanket is also trained with bights therein maintained by the guides 8 and 9, the former of which will be hereinafter referred to and the latter of which is a shaft journaled in bearings in the ends of screws, such as the screw 10 which is adjustable lengthwise (to vary the tension on the blanket) by turning, with a wrench, the worm 11 and so rotating a worm-wheel 12 supported in the frame and forming a nut on the screw. There are other guiding means for the blanket at 13, being shafts or equivalents.

The guide 8 is a beam or roll forming part of what is a rotary structure extending across the frame and journaled in the frame sides, its intermediate portion (here including the beam 8) being eccentric with relation to its journal portions. (Only one of the journal portions and the part of the frame-side in which it is mounted are here shown, it being assumed that the other such portion—being of course concentric with the first—and the part of the frame-side in which it is mounted are duplicates, respectively, of each other.) Thus:

A journal portion is formed by a member 14 which is here a gear, as shown, and to the hub 14a of this gear is secured, in eccentric relation thereto by a screw 15 extending through said hub, a bar 8a on which the beam or roll 8 is preferably free to revolve. Since the bar will usually be of such diameter as to extend beyond that of the hub, and in order to facilitate assembly, there will usually be provided an intermediary disk 16 which is eccentric with the bar and has a boss 16a concentrically countersunk in the hub 14a and is fixed thereto by a screw 17 and which has a flange 16b forming an arcuate seat for the end 55

of the bar, which is concentric with the screw 15. The said member 14 is journaled in ball-bearings 18 in the opposite walls of a housing 19 which forms a part of the frame-side 1. The 5 outer wall of this housing has an arcuate slot 20 concentric with said journal portion and concentric with this said wall may have a dial 21 with which may coact a pointer 22 marked on a stub 23 projecting through the slot from said journal- 10 portion.

The said rotary structure is geared with another rotary structure which here comprises a shaft 25 having a pinion 25a meshing with gear 14 and being journaled in ball-bearings 26 in the 15 housing and having affixed thereto a helically grooved pulley 27. Around this pulley and occupying its groove is the coiled end of a cable 28 which has attached thereto a weight-carrier 29 adapted to support a weight or weights 30.

20 When the guide 9 is adjusted to the left in Fig. 1 the tension on the blanket increases, and when said guide is adjusted to the right such tension decreases. Thus, in the first case the part of the rotary structure with which the blanket has running engagement (i. e., eccentric part 8-8a) is 25 being shifted more and more toward dead-center position, or toward the position where gravity acting on the weight will be augmented by the positive resistance incident to such dead-center 30 condition), wherefore the degree of tension on the blanket increases. Conversely, in the second case said part of the rotary structure with which the blanket has running engagement is being shifted more and more from dead-center position 35 or to the position where the weight alone is coacting with guide 9, wherefore the degree of tension on the blanket decreases.

If a pointer and dial (as a dial marked to show pounds per inch of width of the blanket at given 40 positions of said rotary structure) be provided it is manifest that the precise degree of tension determined by adjustment of worm 11 and hence of guide 9 may be indicated and so observable by the attendant at any time. Since the indicating is in pounds per inch no adjustment or 45 change therein is necessary when a blanket of any width is changed for one of any other width. Sometimes the blanket during a treatment of fabric undergoes change in tension, as by shrinkage incident to wetting, and this being indicated 50

the operator can make the necessary adjustment at 11.

My invention is not limited to application to a so-called "Palmer" machine. Essentially it comprises an endless flexible element, as the 5 blanket; devices maintaining bights in said element and around which it travels, one such device being here the guide 9 and the other comprising gear 14 and bar 8a; supporting structure for said devices having that part thereof in which one 10 such device is supported adjustably relatively to the other device to vary the tension of said element (such part in the present instance being afforded by the screws 10), and one such device being rotatable in said structure and having its 15 bight-maintaining portion eccentric of the axis of rotation of such device; and means (as the cable and weight) yieldingly urging the last-named device in the rotative direction to coact with the other device to hold said element in 20 tensioned state.

Having thus fully described my invention what I claim is:

1. In combination, an endless flexible element and devices maintaining bights therein and 25 around which said element travels, supporting structure for said devices, means in said structure for adjusting one such device to vary the tension on said element and one such device being rotatable in said structure and having its bight- 30 maintaining portion eccentric to the axis of rotation of such device, and means yieldingly urging the last-named device in the rotative direction to coact with the other device to hold said element in tensioned state. 35

2. The combination set forth in claim 1 characterized by the last named means being gravity-actuated.

3. In combination, with supporting structure, a rotatable structure including a member journaled in said structure, a disk arranged in a plane perpendicular to the axis of and flanking the first-named member and having an arcuate seat at the side thereof remote from and arranged eccentrically of said member, a bar having one end portion seated in the seat, and a screw penetrating said member and disk and screwed into the bar and rigidly securing said member, disk and bar together. 40 45

CLIFFORD H. RAMSEY. 50
